(57) **CLAIM**

The ornamental design for an apron with removable straps, as shown and described.

DESCRIPTION

FIG. 1 shows a perspective view of an apron with removable straps, showing my new design.

FIG. 2 shows a front elevation view of the apron with removable straps.

FIG. 3 shows a rear elevation view of the apron with removable straps.

FIG. 4 shows a right side elevation view of the apron with removable straps.

FIG. 5 shows a left side elevation view of the apron with removable straps.

FIG. 6 shows a top plan view of the apron with removable straps; and,

FIG. 7 shows a bottom plan view of the apron with removable straps.

The broken lines shown in the figures show portions of the article that form no part of the claimed design.

1 Claim, 5 Drawing Sheets
